UNITED STATES PATENT OFFICE.

WILLIAM GORDON, OF BOSTON, AND J. WESLEY DODGE, OF MALDEN, MASS.

TRACE-TRIMMING MACHINE.

SPECIFICATION forming part of Letters Patent No. 297,787, dated April 29, 1884.

Application filed January 19, 1884. (No model.)

To all whom it may concern:

Be it known that we, WILLIAM GORDON, of Boston, in the county of Suffolk, and J. WESLEY DODGE, of Malden, in the county of Middlesex, both in the State of Massachusetts, have invented certain Improvements in Trace-Trimming Machines, of which the following is a specification.

This invention has for its object to provide means for quickly and easily trimming the edges of leather traces or straps; and it consists, as a whole, in an organized machine or apparatus composed, first, of a pair of elongated jaws or plates adapted to hold a strap edgewise; and, secondly, of a tool adapted to move upon and trim the projecting edge of the trace held between the jaws.

The invention also consists in certain details, all of which we will proceed to describe and claim.

Of the accompanying drawings, forming a part of this specification, Figure 1 represents a side elevation of a machine embodying our invention. Fig. 2 represents an end view of the same. Fig. 3 represents a bottom view of the trimming-tool. Fig. 4 represents a longitudinal section of the same. Fig. 5 represents an enlarged section on line $x-x$, Fig. 1.

The same letters of reference indicate the same parts in all the figures.

In the drawings, a a' represent parallel elongated jaws or plates of metal. The jaw a is rigidly attached to arms or supports b , which are secured to a base, c . The jaw a' is secured to slides or bars e , which are adapted to move at right angles to the length of the jaws a a' in guides or standards ff , affixed to the base c .

g represents an arbor or rock-shaft journaled in bearings attached to the base c , said arbor being parallel with the jaws a a' . To the arbor g are affixed a series of cams, h , against the perimeters of which the slides e bear, there being preferably a cam for each slide. Springs k are interposed between shoulders on the slides e and the bearings in which the slides move, said springs pressing the slides against the cams, and moving the jaw a' away from the jaw a when the cams are turned so as to

permit such movement. The arbor g is provided with a handle or lever, l , whereby it may be turned in either direction.

m represents an elongated gage bar or plate arranged under the jaws a a' , and adapted to support a trace or strap, n , placed between said jaws before the jaws are caused to grasp the trace or strap. Said gage regulates the extent of the projection of the upper edge of the trace or strap above the upper sides of the jaws, and is preferably made vertically adjustable, so that it can support straps of different widths. To this end the gage-bar is supported by links o , which are pivoted at their upper ends to the bar, and at their lower ends to the base c . Said links permit the bar to move longitudinally, and at the same time rise or fall, as will be readily seen, the height of the bar depending on the inclination of the links. The bar is held in any position to which it may be adjusted by a pin, q , passing through an orifice in the bar m , and one of a series of orifices in an arm, r , affixed to the base c . It is obvious, however, that other means may be used for adjusting and holding the gage-bar.

s represents a trimming-tool, which is composed of a stock or body, 2 , provided with a longitudinal knife or blade, 3 , which is held or clamped between two parts of the stock, as shown in Fig. 5, said stock being divided longitudinally and having screws 44 , which connect its parts or divisions, so that the blade can be easily inserted and removed. The knife-holding parts of the stock are provided with flanges 55 , on which the knife bears. The under surface of the knife is molded between said flanges to the form which is to be imparted to the trace or strap, and the cutting-edge is formed by the intersection of the beveled front end and the molded bottom-surface of the blade. In advance of the blade is a gage-bar, 6 , which limits the thickness of the shaving removed from the trace or strap by the blade. Said gage is a plate of metal rigidly attached to the stock at its front end by a screw or nut, 7 , and adapted to spring upwardly at its rear end into a recess in the stock and pressed downwardly as far as may be desired by a screw,

8, bearing on its upper surface, the screw and the resilience of the bar enabling the portion of the bar that bears on the edge of the strap in advance of the knife to be adjusted as may be desired. The stock is provided with a handle, 9, and a vent or escape orifice, 10, for cuttings. At each side of the gage-bar are downwardly-projecting lips or flanges 12 12, which bear against the sides of the strap when the tool is in operation, and thus guide the tool, keeping the knife in place and preventing it from slipping laterally. The jaws *a a'* should be of suitable length to grasp the entire length of a trace or strap to be trimmed. 15 The trace or strap being in place in the jaws, as shown in Fig. 2, the operator moves the tool rapidly along the projecting edge of the trace, thus trimming it from end to end. Then, by a single movement of the lever *l*, the strap 20 may be released, and after it is turned to expose the other edge the strap may be grasped by another movement of the lever and trimmed on its other edge. Provision is thus made for rapidly and uniformly trimming traces and 25 other long straps, there being no liability of the tool to run off the edge of the strap.

It is obvious that the knife may be formed to impart any desired shape to the trimmed edge.

30 The jaws *a a'* serve as a gage to determine the depth of cut of the knife. The knife-stock projects below the edge of the knife, (see Fig. 5,) and when the strap has been trimmed away so that the knife-stock rides on the jaws the 35 knife ceases to cut.

We claim—

1. The combination, in an organized machine for trimming the edges of leather traces or straps, of a pair of elongated jaws adapted to 40 hold and release a strap and to serve as a gage for the cutter, and a trimming-tool adapted to move along the upper edge of the strap and impart the desired form to the edge thereof, as set forth.

45 2. In a trace or strap trimming machine, the combination of the elongated jaws *a a'*—the one fixed and the other movable—and means,

substantially as described, for moving the movable jaw with relation to the fixed jaw to grasp or release a trace or strap between said 50 jaws, as set forth.

3. In a trace or strap trimming machine, the combination of the elongated parallel jaws—one fixed and the other movable—means, substantially as described, for moving the movable 55 jaw with relation to the fixed jaw, a vertically-adjustable elongated gage arranged to support the lower edge of the strap, and means for positively holding said gage in any position to which it may be adjusted, as set forth.

4. In a trace-trimming machine, the combination of the fixed elongated jaw *a*, the movable elongated jaw *a'*, secured to bars *e*, adapted to slide in bearings *f f*, the rock-shaft *g*, having cams *h*, bearing against the bars *e*, and springs 65 *k*, arranged to press the bars *e* against the cams, as set forth.

5. In a trace-trimming machine, the combination, with the fixed and movable elongated jaws *a a'*, of the elongated gage *m*, located under 70 said jaws, the pivoted links supporting said gage and permitting it to be raised or lowered by an endwise movement, and devices, substantially as described, for holding the gage.

6. The improved trace-trimming tool composed of the stock 2, provided with a cutting-blade, 3, parallel with the bottom of the stock, and with an adjustable gage in advance of said 75 blade and guides at the sides of said gage, as set forth.

7. The tool-stock 2, divided longitudinally into two parts, having lips 5 5 and connecting-screws 4, whereby the blade may be detachably held in the stock, as set forth.

In testimony whereof we have signed our 85 names to this specification, in the presence of two subscribing witnesses this 15th day of January, 1884.

WILLIAM GORDON.
J. WESLEY DODGE.
